TOOTH POWDER RECEPTACLE WITH
RESILIENT POWDER EJECTOR

Teofil L. Bonkowski, Los Angeles, Calif.

Application November 23, 1944, Serial No. 564,798

9 Claims. (Cl. 222—341)

1

This invention relates to receptacles for pulv-
erous or granular substances, from which suc-
cessive partial discharges are to be made.

An object is to facilitate the discharge onto
a definite locus without the need to shake the
container, as, for example, depositing powder
onto the bristles of a toothbrush, thereby avoid-
ing the usual waste of misdirected discharge.

Another object is the attainment of better con-
trol with respect to uniformity of the quantities
dispensed, whereby more or less consistently me-
tered amounts are obtained.

As employed herein, the terms related to and
deriving from the word, powder, are to be inter-
preted broadly enough to include, outside of pul-
verous substances like toothpowder, face talcum
and otherwise, also granular substances, such as,
for example, cube cut tobacco and otherwise.

In the course of examining this specification
and accompanying drawings, there are addition-
al objects and advantages that will disclose them-
selves.

In the drawings—

Figure 1 is a plan view, on a reduced scale, as
seen from the dispensing side of one of many pos-
sible embodiments of the invention, the parts be-
ing shown as they appear in fully extended pos-
ition.

Figure 2 is an enlarged, longitudinal-sectional,
detail view taken substantially on line 2—2 as
shown in Fig. 1.

Figure 3 is a view similar to that of Figure 1
but with the parts as they appear in intermedi-
ate relationship.

Figure 4 is an enlarged, longitudinal-sectional,
detail view of said end section and said closure,
as they appear in the plane 4—4 in Figure 3.

Figure 5 is a view similar to that of Figure 1
but with the parts as they appear in fully re-
tracted position.

Figure 6 is an enlarged, longitudinal-sectional,
detail view of said end section and said closure,
as they appear in the plane 6—6 in Figure 5.

Figure 7 is an enlarged perspective view of said
end section and said closure, but separated from
one another while remaining coaxially aligned,
the wall of said section being shown in half sec-
tion as it appears in the plane 7—7 in Figure 4.

Referring to the drawings, the receptacle that
embodies the instant invention is seen to mainly
consist, on one hand, of the tubular body 11,
whose main section is indicated by 11A, and
whose closure-engaging end section is indicated
by 11B, and, on the other hand, of the closure
12, which is adjointingly embraced by end section

2

11B, and is partly therewith coaxially slidable
into a relationship of full extension, correspond-
ing to Figures 1 and 2, into an intermediate rela-
tionship corresponding to Figures 3 and 4, and
5 into fully retracted position corresponding to
Figures 5 and 6.

The lateral wall of end section 11B, specifically
of the attenuated or neck portion 13 thereof, is
provided with the aperture 13, and the lateral
wall of the closure is provided with the opening
14, which two holes are in longitudinal alignment
with one another, but in transverse misalignment
with one another when the end section and the
closure are in the two said extreme relationships,
15 (see Figures 1, 2, 5 and 6), at which time the in-
terior of the receptacle is substantially isolated
from the exterior thereof, and the contents can-
not be discharged therefrom. When, however,
the end section and the closure are in said inter-
mediate relationship (see Figures 3 and 4), said
two holes are in transverse alignment, with one
another, and since they are always in longitu-
dinal alignment, they are now in axial or substan-
tially complete alignment and now constitute a
20 joint passage, referred to herein by the numerals
13—14, between the interior and the exterior of
the receptacle, through which a limited or par-
tial mass of a total or original mass of powder,
25 not shown but conceivably present inside of the
receptacle, can now be discharged each time that
the described parts are disposed in said inter-
mediate relationship.

Since however each relatively small quantity
dispensed, in the case of most kinds of substances
30 that are indicated for the receptacle, is insuffi-
ciently easy-flowing to guarantee the complete
discharge thereof, a gravity-supplementing ex-
pelling means must be provided for the forcible
expulsion of said limited mass when the two holes
35 are coaxially aligned. This gravity-supplement-
ing means includes the primary expelling means
or curved plate of resilient material 15, conceiv-
ably of spring steel, secured by any suitable means
to any convenient part of body 11. In the in-
stant embodiment, the plate is secured by a rivet
40 to a wall of end section 11B of body 11, although
it may be secured to a wall of the main section
11A instead. The gravity-supplementing means
includes also the secondary expelling means or
45 finger 17, adapted to coact with plate 15, and se-
cured to the closure, together with which it may
be moved axially of the receptacle.

Referring to Figures 1 and 2, the terminal part
50 21 is provided, in the finger-joining end 20
thereof, with a finger-accommodating slot 19,

whose function is to permit the quickly effected withdrawal of part 21 along the abruptly curved end edge of the finger from the hole-containing sections of the walls of the section and of the closure, whereby, when the receptacle is held axially vertical with the dispensing end in an underneath position, a limited mass of powder is allowed to drop down under the force of gravity for entrapment thereof in the space between part 21 and said hole-containing sections, the joint passage being still closed.

Thereupon, now referring to Figures 3 and 4, the receptacle is disposed in a substantially horizontal position, with said two holes underneath and with the place of deposit, for example the bristles of a toothbrush, underneath said holes. The closure 12 is now pushed toward the receptacle 11 to intermediate position bringing said two holes into transverse and consequently axial or complete alinement. The part 21 is forced by the camlike action of the finger, in a transversely outward direction and causing the previously entrapped powder to be thereby forcibly expelled outwardly thru said joint passage now constituted by the two axially alined holes, and deposited as indicated by the group of five arrows onto said toothbrush bristles, neatly and completely without any waste and without resorting to shaking the receptacle. In practice, this stage of intermediate relationship is actually one of brief duration.

Thereupon, as is shown in Figures 5 and 6, the continued inward movement of the closure brings the parts into said relationship of extreme retraction, wherein the opening 14 has now withdrawn from the aperture 13 and into transverse misalinement therewith, thereby closing said joint passage.

In Figures 2, 4, and 6 the aperture 13 and the opening 14 are axially indicated by 13A and 14A respectively.

Referring to Figure 7 as well as to the other figures, it will be noted that the closure is provided with a therefrom angled extension 22, functioning as a detent in that when in the relationship of full extension, it abuts the tapering wall of section 11B, and thereby restrains the closure from its otherwise possible further movement away from section 11B.

The expelling plate 15 is shown in only one of several methods of attachment to the body of the receptacle. It may be supported by a plurality of arms. It may be secured by soldering or frictional retention within a wall-joint of the body itself or otherwise. The expelling plate may be of non-resilient material and even hingedly attached and actuated by a positive-control type of camlike finger that controls the movement of the plate in both directions.

The section 11B need not take the tapered form as shown. In both transverse form and transverse dimension, it may correspond to the main body 11A.

No attempt has been made to describe all of the possible embodiments of the instant invention that can and will suggest themselves to persons skilled in the art. The embodiment described herein and illustrated in the accompanying drawing, has been selected by me as a practical and typical one sufficing to set forth the principles of the invention, whose true scope is set forth in the hereto appended claims.

I claim:

1. In a device for dispensing material from a container, the combination of a closure tele-

scopically mounted with respect to the container, an aperture in the container, a lateral opening in the closure adapted to be aligned with the aperture to form a discharge passage from the container, the closure being selectively movable to a closed position to mis-align the said aperture and opening, and cooperating means within the container and closure and actuated by relative movement therebetween adapted to expel a quantity of material outwardly through the discharge passage, said cooperating means including a resilient finger adapted to move towards said discharge passage.

2. In a device for dispensing material from a container, the combination of a closure slidably mounted axially of the container, an aperture in the container, a lateral opening in the closure adapted to be aligned with the aperture to form a discharge passage from the container, the closure being selectively movable to a closed position to mis-align the said aperture and opening, and cooperating means within the container and closure and actuated by relative axial movement therebetween adapted to expel a quantity of material outwardly through the discharge passage, said cooperating means including a resilient finger adapted to move transverse to the axis of the container towards the discharge passage.

3. In a device for dispensing material from a container, the combination of a closure telescopically mounted with respect to the container, cooperating means on the container and closure to limit the extent of relative movement therebetween, an aperture in the container, a lateral opening in the closure adapted to be aligned with the aperture to form a discharge passage from the container, the closure being selectively movable to a closed position to mis-align the said aperture and opening, and cooperating means within the container and closure and actuated by relative movement therebetween adapted to expel a quantity of material outwardly through the discharge passage, said cooperating means including a resilient finger adapted to move towards said discharge passage.

4. In a device for dispensing material from a container, the combination of a closure slidably mounted axially of the container, cooperating means on the container and closure to limit the extent of axial movement therebetween, an aperture in the container, a lateral opening in the closure adapted to be aligned with the aperture to form a discharge passage from the container, the closure being selectively movable to a closed position to mis-align the said aperture and opening, and cooperating elements within the container and closure actuated by relative axial movement therebetween adapted to expel a quantity of material outwardly through the discharge passage, said elements including a resilient finger adapted to move transverse to the axis of the container toward the discharge passage.

5. In a device for dispensing material from a container, the combination of a closure telescopically mounted with respect to the container, an aperture in the container, a lateral opening in the closure adapted to be aligned with the aperture to form a discharge passage from the container, the closure being selectively movable to a closed position to mis-align the said aperture and opening, and means within the container and closure adapted to expel a quantity of material outwardly through the discharge

passage, said means including cooperating elements on the closure and container, one of said elements being secured to the container and having a free end adapted to move in a direction transverse to the principal axis of the container for expelling the material.

6. In a device for dispensing material from a container member, the combination of a closure member telescopically mounted on the container member for relative axial movement, lateral ports on said members adapted to be brought into registry by relative axial movement of said members to define a discharge passage from the container, cooperating means on said members and positioned therewithin adapted to expel a quantity of material from said container through said discharge passage, said means including an axially immovable element actuated by relative axial movement of said closure member and adapted to move in a direction transverse to the direction of said axial movement.

7. In a device for dispensing material from a container member, the combination of a closure member telescopically mounted on the container member for relative axial movement, cooperating means on said members adapted to define end positions limiting the extent of axial movement in each direction, lateral ports on said members adapted to be brought into registry at an intermediate position along the axial travel between such end positions, said lateral ports when in registry defining a discharge passage from said container member, and means actuated by relative movement of the members from one end position to the other for expelling a quantity of material through said discharge passage, said means including cooperating elements within said members, one of the elements being movable in a direction transverse to the direction of said axial movement.

8. In a device for dispensing material from a container member, the combination of a closure member movably mounted on the container member, cooperating means on said members adapted to define end positions limiting the extent of such movement in each direction, ports on said members adapted to be brought into registry at an intermediate position along the

normal travel between such end positions, said ports when in registry defining a discharge passage from said container member, means actuated by relative movement of the members from one end position to the other for expelling a quantity of material through said discharge passage, said means including cooperating elements within said members, one of the elements being movable substantially in a direction defined by the principal axis of the discharge passage.

9. In a device for dispensing material from a container member, the combination of a closure member telescopically mounted on the container member for relative axial movement, cooperating means on said members adapted to define end positions limiting the extent of axial movement in each direction, lateral ports on said members adapted to be brought into registry at an intermediate position along the axial travel between such end positions, said lateral ports when in registry defining a discharge passage from said container member, means actuated by relative movement of the members from one end position to the other for expelling a quantity of material through said discharge passage, said means including a resilient element mounted within the container member and having a free end adapted to move in a direction transverse to the direction of said axial movement, and a cam element secured within the closure member cooperating with said resilient element to control the transverse movement thereof.
